CHARLES R. THOMAS, JR., OF DREXEL HILL, PENNSYLVANIA, AND BERNARD WICH, OF HERKIMER, NEW YORK, ASSIGNORS TO NATIONAL DESK COMPANY, OF HERKIMER, NEW YORK

DRAWER PARTITION

Application filed December 26, 1931. Serial No. 583,244.

This invention relates to drawers for desks or other articles of furniture, and particularly to adjustable means for securing partitions in the drawers.

The objects of this invention are to provide a drawer with means for securing transverse partitions therein in such a manner as to permit the partition to be readily removed from the drawer and to be shifted to any desired position lengthwise of the drawer; also to provide a clip for securing a partition within a drawer, which clip is provided with means of novel construction for frictionally holding itself in correct relation to a side of the drawer independently of said partition; also to provide a clip of this kind which is arranged to hold a partition in correct position in a drawer and which is held in correct relation to the drawer by the partition; also to improve partition holding means and clips in other respects hereinafter specified.

In the accompanying drawings:

Fig. 1 represents a fragmentary perspective view of the interior of a drawer having partition holding means embodying this invention arranged thereon;

Fig. 2 is a fragmentary top plan view of a drawer, partly in section;

Fig. 3 is a fragmentary sectional elevation thereof, on line 3—3, Fig. 2;

Fig. 4 is a sectional plan view thereof, on line 4—4, Fig. 3;

Fig. 5 is a side elevation of a partition retaining clip removed from the drawer, the dotted lines representing the slots in the drawer into which the upper and lower ends of the clip are pressed;

Fig. 6 is a sectional elevation thereof, on line 6—6, Fig. 2;

Fig. 7 is a face view of a metal stamping from which a clip may be formed.

A represents the front wall of a drawer, B the bottom thereof and C the sides of the drawer, which may be provided with slots c to receive the side edges of the bottom B. All of these parts are commonly used in drawer construction and are illustrated merely to show how our invention may be applied to a drawer. D represents a partition arranged

to extend transversely of the drawer from one side thereof to the other and this partition may rest upon the bottom B of the drawer. These partitions are ordinarily held in place by having the ends thereof arranged in upright slots cut in the sides of the drawer, but these slots do not permit adjusting of the partitions to suit all different conditions and also necessitate a separate operation for cutting the upright slots in the drawer sides.

In accordance with this invention, each drawer side has a pair of slots 9 and 10 extending lengthwise on the inner face thereof, and clips E are provided which form connections between the partition and the side walls. These clips have portions extending into the slots 9 and 10 and portions engaging the ends of the partition D. These clips are preferably formed of resilient material, such as sheet metal, and may be formed from stampings, such as the one shown in Fig. 7, having a body portion 12 which, when the clip is in use, lies flat against the side of the drawer between the slots 9 and 10 and mainly between one end of the partitions and the drawer side. The clip is also preferably provided at opposite sides of the body portion with lugs or partition holding projections 14 which may be bent along the broken lines 15 in Fig. 7, into positions to form between them a channel or space into which an end of the partition D may enter.

At the upper and lower ends of the body portion 12 are formed arms which may be bent along broken lines 16 shown in Fig. 7, in a direction opposite to the direction in which the lugs 14 are bent. In the construction shown, a pair of arms 17 is provided at each end of the body portion 12, the arms of each pair extending in opposite directions. The clip is preferably made of spring metal and the arms 17 are consequently sprung either outwardly or inwardly to engage either of the shoulders formed by the two walls of each of the opposed slots 9 and 10, the arms in the clip shown in the drawings being sprung outwardly, as clearly shown in Fig. 6, so that when the arms are placed into the slots 9 and 10, the upper and lower arms must first be pressed toward each other

against the spring action of the metal of the clip. Similarly, the lugs 14 which engage the partition are also sprung toward each other, as clearly shown in Fig. 4, so that the 5 outer edges of the lugs 14 yieldingly grip the partition B. The spring action of the arms 17 serves to frictionally engage the walls of the slots 9 and 10 in such a manner as to hold the partition D in correct upright position and four arms are preferably employed, 10 since they insure the holding of the partition in upright position, although any desired number of these arms may be employed. The arms, by their engagement with the opposed shoulders, also serve to frictionally resist movement of the partition lengthwise of the drawer, but if desired, for the purpose of adjusting the partition, the clips E may be slid lengthwise of the grooves 9 and 10 15 by the use of sufficient force to overcome the friction. In order to cooperate to best advantage with the arms of the clips the grooves or slots 9 and 10 are preferably cut into the sides of the drawer at substantially right 20 angles to the inner faces of the sides. This also results in the minimum weakening of the drawer sides by the slots and reduces the tendency of either edge portion of a slot to become broken or split. 25 By having the lugs 14 yieldingly grip the partition D, the same is securely held against rattling and also the clips will readily accommodate themselves to variations in thickness of the partitions. It will be noted that 30 by the use of these clips, no pressure is applied endwise to the partition, which might tend to warp the partition or bend the same to assume a curved or bowed form. The partition can be easily removed from the 35 drawer by lifting the same vertically so that the ends of the partition slide in the space between the lugs 14.

The means described for holding the partitions in drawers are inexpensive to apply, 40 in that the clips can be readily formed of a small piece of sheet metal and the slots 9 and 10 can be cut in the drawer sides during the same operation that the usual groove α is cut therein. The clips permit the partitions 45 to be secured at any distance from the ends of the drawer so that the interior of the drawer can be divided into spaces of such size as to best accommodate the material which is placed in the drawer.

50 The clip described also has the advantage that the upright body portion thereof is arranged between the side wall and the adjacent end of the partition and the lugs 14 lie in close contact with the partition, while the 55 arms 17 are entirely out of the way in the grooves 9 and 10 so that none of the space within the drawer available for storage of articles is taken up by the clips E, nor do the clips interfere with placing articles into 60 or removing them from the drawer.

The construction described has the additional advantages that any desired number of partitions may be used in a drawer depending only upon the space required by the clips lengthwise of the drawer sides, and if a 70 partition is not required, it is merely necessary to pull the same upwardly out of the drawer, whereupon the clips can be quickly drawn out of engagement with the slots and removed from the drawer. As long as a 75 partition is in its operative position in the drawer, the two clips holding the partition will be held against movement out of their operative positions so that the clips cannot accidentally get out of their operative positions unless the partitions held by the clips are first removed.

The construction also has the advantage 80 that the grooves 9 and 10 do not detract in any way from the appearance of the interior of the drawer, as do the upright slots heretofore employed, for the reason that the slots 9 and 10 shown in the drawings, are spaced well below the top of the drawer where they 85 are scarcely noticeable.

We claim as our invention:

1. The combination with a drawer having 90 sides each provided with a pair of parallel grooves extending lengthwise thereof and which are formed with horizontal walls, and a transverse partition, of a pair of clips for 95 adjustably securing said partition crosswise of said drawer, each of said clips including a flat, upright body portion terminating at its upper and lower ends in spring arms bent in a plane at an angle to said body portion to enter said grooves, and said arms being further bent in a plane parallel to the plane of 100 said body portion each to engage a horizontal wall of one of said grooves and yieldingly hold the clip by friction in any position lengthwise of said grooves, the body portion of each clip having parts adapted to embrace the adjacent end of the partition to yieldingly hold the same in the desired position in 105 said drawer.

2. Clips for releasably securing partitions 110 to two parallel drawer sides, each side having a pair of parallel grooves extending lengthwise thereof, each clip including an upright body portion having spring arms bent at an angle thereto at the upper and lower ends thereof and adapted to enter said 115 grooves, and a pair of upright ears bent in a direction opposite to said arms and adapted to releasably engage the opposite faces of a partition, said arms exerting opposed spring pressure against the walls of said grooves in a vertical direction to frictionally hold said partition in fixed relation to the drawer, and whereby said clips will be retained in said 120 grooves by said spring pressure when said partition is disengaged from said clips.

3. A clip for securing a partition to a 125 drawer side provided with a pair of parallel 130

horizontal grooves extending lengthwise thereof and formed with horizontal walls, said clip including an upright body portion having horizontal spring arms at the upper 5 and lower ends thereof bent at an angle there-to to enter said grooves, said arms having opposed bent portions formed to yieldingly press against opposite horizontal walls of said grooves to yieldingly and frictionally 10 hold the clip against movement lengthwise of the drawer side, and said clip having an upright recess adapted to receive and support an end of a partition.

4. A clip for securing a partition to a 15 drawer side provided with a pair of parallel grooves extending lengthwise thereof, said clip being made of sheet metal including an upright body portion arranged to be positioned between the drawer side and the ad- 20 jacent end of the partition, upper and lower spring arms extending forwardly and rear- wardly from said body portion with refer- ence to the drawer sides and bent over and away from said body portion so as to enter 25 said grooves, and said arms being respective- ly bent in opposite directions and in a verti- cal plane to yieldingly engage opposed walls of said grooves and frictionally hold said clip in said grooves, and lugs at the sides of 30 said body portion formed from the metal be- tween upper and lower arms and bent rela- tively to said body portion in a direction opposite to that in which said arms are bent and adapted to engage the opposite faces of a 35 partition near the ends thereof.

5. Clips for adjustably securing partitions to supporting side walls each having opposed, substantially parallel shoulders, said clips having spring arms formed to yieldingly en- 40 gage said opposed shoulders to facilitate ad- justment of said clips lengthwise of said side walls and to frictionally retain said clips on said side walls independently of said parti- tions, said clips further having means for en- 45 gaging said partitions to hold the same in de- sired relation to said side walls.

6. A clip for securing a partition to a sup- porting side wall having opposed substantial- 50 ly parallel shoulders, said clip having a body portion provided with partition engaging means, and opposed spring arms at opposite ends of said body portion formed to yieldingly engage said opposed shoulders and fric- tionally retain said clip on said side wall.
